UNITED STATES PATENT OFFICE.

ERNEST S. KNEELAND, OF MALDEN, MASSACHUSETTS.

TAPE-MOISTENING DEVICE.

1,171,056.

Specification of Letters Patent.

Patented Feb. 8, 1916.

Application filed January 20, 1915. Serial No. 3,297.

To all whom it may concern:

Be it known that I, ERNEST S. KNEELAND, a citizen of the United States, residing at Malden, in the county of Middlesex and 5 State of Massachusetts, have invented a new and useful Tape-Moistening Device, of which the following is a specification.

The device forming the subject matter of this application is adapted to be employed 10 for moistening adhesive tape of that general sort which commonly is dispensed in rolls.

One object of the present invention is to provide novel means whereby the end of 15 the tape will be elevated with respect to the moistening device, after a predetermined length of the tape has been severed, the construction being such that the free end of the tape on the roll will not adhere to the 20 moistening roller, or be left in a plastic condition unfit for further use.

Another object of the invention is to provide in a device of the class described, a single element which exercises three functions, to wit, a means for lifting the end of 25 the tape after a predetermined length has been severed therefrom; a means for guiding the tape while the tape is passing from the delivery mechanism to the moistening device; and a means for engaging the moistening roller, thereby to spread the moistening liquid on the moistening roller and to cause surplus liquid to flow back into the tank.

35 Another object of the invention is to provide a novel form of brake mechanism which, coöperating with the roll of tape, renders the tape efficient as a means for depressing a resilient member, so that the resilient member will engage the moistening 40 roller, and so that the tape may pass readily into coacting relation with respect to the moistening roller.

It is within the scope of the disclosure to 45 improve generally and to enhance the utility of devices of that type to which the present invention appertains.

With the above and other objects in view which will appear as the description proceeds, the invention resides in the combination and arrangement of parts and in the details of construction hereinafter described and claimed, it being understood 50 that changes in the precise embodiment of the invention herein disclosed can be made within the scope of what is claimed, with-

out departing from the spirit of the invention.

In the accompanying drawings:—Figure 1 shows the invention in side elevation; Fig. 60 2 is a top plan wherein sundry parts have been broken away; Fig. 3 is a vertical longitudinal section showing the parts in the positions which they will assume while the tape is being advanced and moistened; Fig. 65 4 is a fragmental vertical longitudinal section similar to Fig. 3 showing certain of the parts in the positions which they will assume after the tape has been torn off the cutter; Fig. 5 is a vertical transverse section taken through the tape delivery mechanism.

In carrying out the present invention there is provided a supporting structure which is denoted generally by the numeral 75 1. The supporting structure 1 comprises side walls 2, an end wall 3, an intermediate wall 4 and a bottom 5, the end wall 3, the intermediate wall 4, the bottom 5 and the side walls 2 coöperating to define at one 80 end of the supporting structure, a tank 6 adapted to receive water or other liquid whereby the tape is moistened. At the rear end of the supporting structure 1, the side walls 2 are connected by an upstanding stop 85 strip 7, the functions of which will be made manifest hereinafter. The side walls 2 are provided adjacent the rear end of the device with upright standards 8.

The moistening device preferably takes 90 the form of a roller denoted generally by the numeral 9 and adapted to dip into the liquid contained within the tank 6. The roller 9 may be variously fashioned but in the present instance the roller is shown of 95 composite form, embodying a shaft 10 journaled for rotation in notches 11 formed in the upper edges of the side walls 2. Secured to the shaft 10 are spaced disks 12 surrounded by a cylindrical shell 14. The 100 shell 14 may be secured to the disks 12 or it may rotate thereon.

A cutter is employed for severing the tape, the cutter in the present instance being 105 shown in the form of a strip or bar 15 extended across the supporting structure 1 and connected with the side walls 2 by means of securing elements 16. The cutter 15 is located slightly to the rear of the roller 9 and is disposed in approximately horizontal 110 relation with respect to the upper portion of the roller. The side walls 2 are

united, to the rear of the intermediate wall 4 by a cross pin 17. The invention includes a forwardly and upwardly curved yieldable, tape engaging member in the form of 5 a spring tongue 18 which may be fashioned into an eye 19 engaging the cross pin 17, one end of the tongue being prolonged upwardly to form an arm 20 terminating in a forwardly extending finger 21 which bears 10 against the intermediate wall 4. The construction of the spring tongue 18 and the manner of mounting the same is such that the free, upper end of the tongue 18 tends normally to exert a pressure against the 15 under side of the cutter 15 as will be understood clearly from Fig. 4. Disposed to the rear of the spring tongue 18 is a guide roller 22 which may be carried by a shaft 23 journaled in or supported by the side walls 2.

20 The invention comprises a tape delivery mechanism, the same including a shaft 24 having reduced trunnions 25 at its ends, the trunnions 25 being journaled in notches 26 formed in the upper ends of the standards 25 8. The reduced trunnions 25 define shoulders 27 in the shaft 24 which, coöperating with the standards 8, prevent the shaft 24 from moving endwise as will be apparent from Fig. 5. The tape which is to be moistened ordinarily is sold in the form of a roll 28 wrapped about a core 30. The shaft 24 passes through the core 30. The free end of the roll of tape is denoted by the numeral 29.

35 Loosely mounted on the shaft 24 are disks 31, adapted to bear against opposite sides of the roll 28 of tape, the construction being such that the shaft may be inserted readily into the disks. The disks 31 as 40 shown best in Fig. 3, are provided with shoulders 32 adapted to coact with the stop strip 7 to prevent the disks from rotating. Brake elements in the form of upwardly extended, resilient arms 33 are provided, the 45 lower ends of the arms 33 being attached by means of securing devices 34 to the inner faces of the standards 8. The upper ends of the arms 33 converge and are slotted as shown at 35 to receive the shaft 34, the upper ends of the arms 33 pressing yieldingly on the outer faces of the disks 31, thereby to 50 compel the disks to exert a retaining and braking pressure on the roll 28 of tape.

In preparing the machine herein disclosed 55 for use, the shaft 24 is inserted through the disks 31 and through the core 30, the roll 28 of tape thus being disposed between the disks 31. The arms 33 are spread apart, the disks 31 and the roll 28 of tape are inserted 60 between the arms 33, and the trunnions 25 on the shaft 24 are inserted into notches 26 in the standards 8. Thus the roll of tape is supported for rotation, and the arms 33 are so positioned that they will bear yieldingly 65 upon the outer faces of the disks 31. The

free end 29 of the roll 28 of tape is passed beneath the guide roller 22, across the top of the spring tongue 18 and beneath the cutter 15. The parts then appear as shown in Fig. 4 and, by the action of the spring tongue 18, the free end 29 of the strip of tape is pressed upwardly against the under face of the cutter 15.

When it is desired to sever a length of tape from the roll, the free end 29 of the tape is drawn to the left, referring to Figs. 3 and 4, the free end of the tape passing across the top of the moistening roller 9 with obvious results. While the tape is being drawn out, the free, upper end of the spring arm 18 is 75 swung downwardly, as shown at Fig. 3. This downward movement of the free upper end of the tongue 18 is brought about for two purposes. First, in order that the free end 29 of the tape may engage with the moistening roller 9; and secondly, in order that the free upper end of the spring tongue 18 may bear upon the periphery of the roller 9, as shown in Fig. 3. When the free upper end of the tongue 18 bears on the roller 9 as 80 shown in Fig. 3, the water on the roller is distributed, and at the same time, the surplus water on the roller is compelled to pass 85 backwardly into the tank 6, thus preventing the tape from being moistened to too great an extent.

In connection with the spring tongue 18 when the tape is disposed adjacent the roller 9 as shown in Fig. 3, it is to be observed that the disks 31 and the brake arms 33 100 exercise an important function, since they retard the tape enough so that the latter, when pulled upon, will depress the spring tongue 18 into the position shown in Fig. 3.

When a sufficient length of tape has been 105 unreeled, the tape is torn off across the cutter 15. So soon as this cutting off of the tape has been effected, the spring arm 18 moves into the position shown in Fig. 4 and elevates the end of the roll of tape, so 110 that the said end cannot come into contact with the moistening roller 9. Consequently, after the tape has been severed, the end of the roll of tape does not adhere to the roller 9 and the end of the tape on the roll is not 115 left in a moist and sticky condition, to adhere to the fingers of the operator. In this connection it is to be noted that when the end of the tape on the roll is left in a moist and sticky condition, so much of the tape 120 as has been moistened, is generally torn off and wasted, since it is manifestly impracticable to operate the machine properly and to apply the severed length of tape with advantage, if the free extremity of the tape 125 leading from the roll remains moist and sticky as a result of a preceding operation.

Having thus described the invention, what is claimed is:

1. In a tape moistener, a moistening

- means; tape delivery mechanism; a relatively fixed cutter located between the moistening means and the tape delivery mechanism; and a resilient means operating beneath the cutter to bind the tape against the cutter and to lift the end of the tape with respect to the moistening means after the tape has been severed by the cutter, the cutter coacting with the resilient means to limit the lifting movement thereof.
2. In a tape moistener, a tank; a moistening roller coöperating with the tank; a tape delivery mechanism; a cutter located adjacent the moistening roller; and a yieldably acting member located adjacent the cutter and constituting means for lifting the end of the tape after the tape has been severed by the cutter, the yieldably acting member being tape actuated to bear on the roller while the tape is being advanced.
3. In a tape moistener, a tank; a moistening roller coöperating with the tank; a tape delivery mechanism; a cutter located adjacent the moistening roller; and a yieldably acting member located adjacent the cutter and constituting means for lifting the end of the tape after the tape has been severed by the cutter, the yieldably acting member being tape actuated to bear on the roller while the tape is being advanced, and constituting a tape support while the tape is being advanced.
4. In a tape moistener, a tank; a moistening roller coöperating with the tank; a tape delivery mechanism; a cutter located adjacent the moistening roller; and a yieldably acting member located adjacent the cutter and constituting means for lifting the end of the tape after the tape has been severed by the cutter, the yieldably acting member being tape actuated to bear on the roller while the tape is being advanced; and means for exerting a brake-pressure on the delivery mechanism thereby to tighten the tape and to render the tape efficient as

a means for actuating the yieldable member with respect to the roller.

5. In a tape moistener, a supporting structure including a stop; a tape receiving shaft carried by the supporting structure; tape engaging disks journaled on the shaft and having shoulders coacting with the stop; yieldable brake elements carried by the supporting structure and bearing on the outer faces of the disks; a moistening device; a cutter located adjacent the moistening device; and a tape engaging means located adjacent the cutter, the tape engaging means being yieldable to permit the tape to engage the moistening device while the tape is retarded by the action of the disks and the brake elements and being movable to elevate the end of the tape with respect to the moistening device after the tape has been severed by the cutter.

6. In a tape moistener, a supporting structure including a stop; a tape receiving shaft carried by the supporting structure; tape engaging disks journaled on the shaft and having shoulders coacting with the stop; yieldable brake elements carried by the supporting structure and bearing on the outer faces of the disks; a tank; a moistening roller coöperating with the tank; a cutter located adjacent the moistening roller; and a tape-engaging means located adjacent the cutter, the tape engaging means being yieldable to bear upon the roller when the tape is retarded by the disks and the brake elements, and being movable to elevate the end of the tape with respect to the moistening roller after the tape has been severed by the cutter.

In testimony that I claim the foregoing as my own, I have hereto affixed my signature in the presence of two witnesses.

ERNEST S. KNEELAND.
